(57) CLAIM

The ornamental design for postcard optical disc mailer, as shown and described.

DESCRIPTION

FIG. 1 is a top perspective view of the postcard optical disc mailer showing my new design;

FIG. 2 is a bottom perspective view thereof;

FIG. 3 is a top plan view thereof; and,

FIG. 4 is a bottom plan view thereof.

The broken line showing of a portion of the postcard optical disc mailer is included for the purpose of illustrating environmental structure and forms no part of the claimed design.

1 Claim, 2 Drawing Sheets

FIG. 1

FIG. 4
